CLAIM

The ornamental design for a baby stroller frame, as shown and described.

DESCRIPTION

FIG. 1 is a first front perspective view of a baby stroller frame showing my new design with a seat and wheels shown in broken lines.

FIG. 2 is a second front perspective view thereof without the seat.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof, the right side elevational view being a mirror image thereto.

FIG. 8 is a front perspective view of a second embodiment thereof.

FIG. 9 is a top plan view thereof.

FIG. 10 is a bottom plan view thereof.

FIG. 11 is a front elevational view thereof.

FIG. 12 is a rear elevational view thereof; and,

FIG. 13 is a left side elevational view thereof, the right side elevational view being a mirror image thereto.

The broken lines are for illustrative purposes only and form no part of the claimed design.
